DIRECTION FINDING SYSTEM WITH
MICRORAYSAndré G. Clavier, Glen Ridge, N. J., assignor to
International Communications Laboratories,
Inc., Newark, N. J., a corporation of New YorkApplication December 16, 1931
Serial No. 581,363

4 Claims. (Cl. 250—11)

This invention relates to direction finding systems with micro-rays.

In my U. S. Letters Patent No. 1,928,408 I have disclosed a signaling system which employs 5 micro-rays and a method of, and apparatus for, producing and detecting these rays.

In U. S. Letters Patent No. 1,927,394 granted to Rene H. Darbord and myself, there is disclosed a signaling system with micro-rays in which relay stations are used between the transmitting 10 and receiving ends of the system. In the last mentioned patent it is also disclosed that such systems may be used for direction finding. This application is a continuation in part of said last 15 mentioned patent.

At the present time, when a ship is in the midst of a fog it is customary for the ship to blow its foghorn continually in order to give warning of 20 its presence to any other ships which may be in the vicinity. In spite of this precaution many collisions occur and a great many others are narrowly averted. When a foghorn is heard in a heavy fog, it is difficult to tell from what direction the sound is coming. Fog, therefore, constitutes 25 probably the principal hazard of navigation.

An object of this invention is to provide a direction finding system which will be very useful for short distances and particularly in the case of fog.

Fog also presents one of the major hazards to 30 aerial navigation, and particularly when attempting to land aircraft. If the ground is obscured by fog there is danger, with the present type of aircraft in general commercial use, that an attempted landing will result in disaster. This invention will also be useful in connection with 35 aerial navigation, and particularly in locating an invisible airport and in making a blind landing.

In the drawing:

40 Fig. 1 shows schematically one form of my invention;

Fig. 2 shows schematically another form of my invention; and

Fig. 3 shows a circuit which may be used in 45 connection with either of the other figures.

In Fig. 1 means for detecting micro-rays is enclosed within the container 1 and connected by means of transmission line 2 to an antenna consisting of two pairs of antenna sections 3—3' and 50 4—4' arranged at right angles to one another. The antenna is at the focus of a parabolic reflector 5. A rotatable reflecting screen 6 is mounted with its center opposite the antenna and its axis parallel to the plane of the opening of reflector 5. The screen 6 is supported upon a suitable

standard 7 and may be rotated by any suitable means, such as worm 8 and pinion 9. The screen 6 is square and its sides should be considerably longer than the longest wavelength for which the direction finder is designed, and should never be shorter than twice the longest wavelength, for best reception. It is also advisable to have the screen large with respect to the parabolic reflector 5, so that it will not be completely obscured by the reflector and can, therefore, receive waves coming from the direction of the reflector. If any transmitting station is in range for transmitting micro-rays, the screen as it revolves will come to a position where it reflects these rays onto the antenna system, and they will be detected in the detector. If desired, a scale can be provided, such as that shown in Fig. 2, for giving an indication of the direction from which these waves are coming. The transmitting station will be arranged similarly to the receiving 60 station, the only difference being that at the transmitter the apparatus will be adjusted for generating oscillations and transmitting them. If desired, a direction finding system may consist of two sets of apparatus, such as that shown in Fig. 1 or 2, one unit being used only for transmission and the other unit being used only for reception. Or a device, such as that shown in Fig. 1, may be operated by using it as a transmitter for a certain interval, during which time 65 if desired the reflecting screen 6 may be made to rotate rapidly in order to send a signal which is as nearly continuous as practicable in every direction, and the apparatus may then be adjusted for detection and the screen 6 revolved slowly 70 to pick up any waves which may be incident thereon.

In Fig. 2 an oscillating or detecting system is enclosed in the container 1 connected by means of transmission line 2 to the antenna system 95 3—3', 4—4' which is arranged at the focus of a parabolic reflector 5. In this case the reflector 5 is mounted with the plane of its opening horizontal and the reflecting screen 6 is mounted on a shaft 7 which turns about a vertical axis and may be turned by any suitable means, such as gears 10 and 11. A dial 12 has suitable scale devices thereon which are indicated by a pointer 13. The antenna system in both cases utilizes four quarter wave antennæ arranged at right 100 angles.

Micro-rays are peculiarly free from fading, static, or other disturbances and are, consequently, very reliable for use as a fog signal. They require an unobstructed path so that the appa- 110

ratus will have to be mounted at a point where there is a maximum unobstructed view.

One manner in which the invention may be usefully applied to aerial navigation is by equipping aircraft with micro-ray devices mounted at the bottom of the fusilage, and equipping airports with suitable transmitters which are located in the center of the field, and sending a conical beam upward. This beam may be arranged so that at a height of 500 ft., say, it spreads out just to the point of covering the landing field. At several thousand feet it will, of course, cover a considerably larger area. An aviator may be guided to the landing field by means of direction finders or radio beacons, such as those now in use, and when directly over the field will receive a signal from the micro-ray transmitter informing him of this fact. By keeping within the micro-ray beam he may then circle down over the field.

The micro-ray direction finding system may, of course, also be used for telephone conversations or for telegraphy. When the aviator is ready to make a landing, he may be informed of the direction from which the wind is blowing. The transmitting apparatus may be movably mounted so that it can be moved to transmit at an angle in the opposite direction, and if desired the beam may be narrowed by changing the reflector 5. The aviator may then again pick up the beam and follow it down to the ground. This will land him at the center of the field so that he will clear obstacles outside of the field and have sufficient space in which to roll to a stop after landing.

In Fig. 3 the container 1 has in it a micro-ray tube having a cathode 14, an oscillating electrode 15, and a repulsion electrode 16. A battery 17 supplies current to the cathode through a resistance 18, a battery 19 supplies potential to the repulsion electrode through a potentiometer 20, and a battery 21 supplies potential to the oscillating electrode through a potentiometer 22 in series with a choke coil 23. Modulating signals

may be applied to the tube through transformer 24 and condenser 25, or when the tube is used as a detector the detected signals may be taken from the circuit by means of these elements.

What is claimed is:

1. The method of determining the direction of signalling impulses in a micro-ray system having a paraboloid reflector with a rotatably mounted reflecting screen positioned in front of the opening thereof, which comprises adjusting said system for the detection of signals and slowly revolving said screen whereby a signal is impinged upon said paraboloid reflector.

2. The method of transmitting directional waves in a micro-ray signalling system having a paraboloid reflector with a rotatably mounted screen positioned in front of the opening thereof, which comprises generating high frequency impulses and rapidly rotating said screen whereby high frequency impulses reflected by said reflector are broadcast.

3. A micro-ray directional system including a paraboloid reflector having an antenna disposed substantially at its focal point, a screen rotatably mounted and disposed a predetermined distance in front of the opening in said paraboloid reflector, and means associated with said screen adapted to cause its rotation whereby said screen may be rotated rapidly when said system is used as a directional transmitter and slowly when said system is used as a directional detector.

4. A micro-ray directional system including a paraboloid reflector having quarter-wave antennæ arranged at right angles to each other and disposed substantially at its focal point, a rotatably mounted screen disposed a predetermined distance in front of the opening in said paraboloid reflector, and means adapted to cause rotation of said screen whereby said screen may be rotated rapidly when said system is used as a directional transmitter and slowly when said system is used as a directional detector.
